TENT POLE CONNECTOR

Gordon Hampton Salt, Birmingham, England, assignor
to The Hampton Works (Stampings) Limited, Birmingham, England

Filed Nov. 20, 1970, Ser. No. 26,090

Claims priority, application Great Britain May 20, 1970

Term of patent 14 years

Int. Cl. D8—08

U.S. Cl. D8—236

FIG. 1.

FIG. 2.

FIG. 3.

FIG. 1 is a top perspective view of the front and one side of a tent pole connector showing one embodiment of my new design;

FIG. 2 is a similar top perspective view showing a further embodiment of my new design, and

FIG. 3 is also a similar top perspective view showing yet another embodiment of my new design.

The top perspective view of each embodiment from the rear and other side thereof is a mirror image of that shown in the drawings.

I claim:

The ornamental design for a tent pole connector, as shown and described.
